UNITED STATES PATENT OFFICE.

CHARLES H. METZ, OF WALTHAM, MASSACHUSETTS.

DESIGN FOR A PEDAL-SHAFT.

SPECIFICATION forming part of Design No. 25,336, dated March 31, 1896.

Application filed May 22, 1895. Serial No. 550,274. Term of patent 7 years.

To all whom it may concern.

Be it known that I, CHARLES H. METZ, of Waltham, in the county of Middlesex and State of Massachusetts, have invented and produced a new and original Design for Pedal-Shafts, of which the following is a specification, reference being had to the accompanying drawing, forming part thereof.

The drawing represents a pedal-shaft illustrating my new design.

The leading feature of my design consists in the faceted abutment on the shaft.

In the drawing, 5 represents the main por-

tion of the shaft, and 6 is an enlarged portion thereof, the surface of this enlargement having the panels or facets 7 7 extending along the enlarged portion, each panel lying in a plane at an angle with the adjoining panel.

What I claim is—

The design for a pedal-shaft as herein shown and described.

CHARLES H. METZ.
